JOHN V. OSTERHOUT, OF BRIDGEPORT, CONNECTICUT; ELIZABETH K. OSTERHOUT
ADMINISTRATRIX OF SAID JOHN V. OSTERHOUT, DECEASED

INTERNAL-COMBUSTION ENGINE

Application filed May 26, 1926. Serial No. 111,751.

This invention relates to an internal combustion engine, and an object of the invention is to provide an internal combustion engine having mechanism for insuring that the explosive mixture fed to each cylinder of the engine can have the proper proportions of gas and air.

A further object is to provide adjustable means for modifying the richness of an explosive mixture fed to a cylinder of an internal combustion engine.

A further object is to provide a separate mixing chamber for each cylinder of an internal combustion engine, and to equip each mixing chamber with means for modifying the richness of an explosive mixture fed to the cylinder.

A further object is to provide a separate mixing chamber for each cylinder of an internal combustion engine, and to equip each mixing chamber with an adjustable air valve for modifying the richness of an explosive mixture fed to a cylinder independently of the mixture fed to all other cylinders.

A further object is to provide an internal combustion engine having a separate mixing chamber for each cylinder, which mixing chamber has an adjustable compensating, equalizing or modifying valve or device adapted to be manipulated by the sucking action of a piston in the corresponding cylinder to insure that the explosive mixture fed to a cylinder will have the proper proportions of gas and air.

A further object is to provide each cylinder of an internal combustion engine with a separate mixing chamber, and to provide each mixing chamber with an adjustable compensating, equalizing, or modifying valve or device adapted to be opened by reason of suction exerted by a piston in the corresponding cylinder in such manner as to dilute a too rich mixture in said mixing chamber.

A further object is to provide an internal combustion engine which includes a carburetor, cylinders having pistons, an intake manifold leading from the carburetor toward the cylinders, a plurality of separate mixing chambers all adapted to be communicated with by the intake manifold and each adapted

to communicate with a cylinder, and an air valve in each mixing chamber adapted to be opened by reason of suction exerted by a piston in the corresponding cylinder to dilute a too rich mixture in the mixing chamber.

A further object is to provide between the intake manifold and the cylinders of an ordinary internal combustion engine, a unifold consisting of separate compartments or mixing chambers, one for each cylinder and adapted to be communicated with by said intake manifold, and to provide in each compartment or mixing chamber an inwardly opening check valve adapted to be opened by suction exerted by a piston in a cylinder with which said compartment or mixing chamber communicates during the suction stroke of said piston.

A further object is to provide check valves between each compartment or mixing chamber and said intake manifold.

A further object is to provide in the intake passage of an internal combustion engine a blow out valve adapted to care for back firing.

A further object is to provide in an internal combustion engine a mixing compartment or chamber adapted to be communicated with by an intake manifold and adapted to communicate with a cylinder, and to provide in said compartment an inwardly opening valve adapted to allow entry of atmospheric air to said compartment or chamber and an outwardly opening valve constituting a blow out for back firing.

A further object is to provide a unique and simple air resistance device at the carburetor of the improved internal combustion engine.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the

invention and the scope of the appended claims.

In the accompanying drawing forming a part of this specification,

Fig. 1 is a perspective view of an internal combustion engine in which the features of the invention are incorporated;

Fig. 2 is an enlarged fragmentary sectional view disclosing a part of an engine cylinder, a part of the intake manifold, and a compartment or mixing chamber of the engine of Fig. 1;

Fig. 3 is a fragmentary sectional view as on line 3—3 in Fig. 2; and

Fig. 4 is an enlarged fragmentary sectional view of the air resistance device at the carburetor.

With respect to the drawing and the numerals of reference thereon, 10 represents, generally, an internal combustion engine, 11 the cylinders thereof, 12 the cylinder block having inlet passages 13, one to each cylinder, each controlled by explosive mixture inlet valve 14. Numeral 15 denotes, generally, a carburetor, and 16 indicates an intake manifold leading from the carburetor toward the cylinders. All of the parts mentioned may be of ordinary or preferred construction. As disclosed, the carburetor includes a tubular member 17 closed at one end 18 and having inwardly opening doors 19 hinged in its side walls as at 20, whereby to provide resistance to air entering the intake manifold via the doors in a manner which will be understood. A ring 21 about the tubular member 17 has spaced openings 22 and is adapted to be manipulated to cover spaced openings 23 in said tubular member or to allow openings 22 and 23 to completely or partially coincide, whereby to provide any desired carburetor adjustment.

The engine disclosed has four cylinders, although it could have a different number of cylinders. Numeral 24 represents what I prefer to style a unifold. As disclosed, the unifold is of oblong shape and consists of four separate compartments or chambers 25 each communicating as at 26 with a passage 13 in the cylinder block and leading toward 50 a cylinder, and each being secured as at 27 to an outlet 28 of said intake manifold. The unifold may be secured upon the engine block in any ordinary or convenient manner. Each compartment or chamber is independent of all other compartments or chambers, 55 representing walls between the compartments or chambers.

The inlet passage 30 of each compartment or chamber 25, which inlet passage is in communication with an intake manifold outlet 28, is provided with a check valve 31 adapted to allow entry of explosive mixture from the intake manifold to said compartment or chamber. As disclosed, each valve 31 is 65 adapted to be opened by vacuum created in

a cylinder upon the intake stroke of a piston, although each valve 31 could be positively operated in any convenient manner. A stem 32 upon each valve 31 is slideable in a spider 33 within said passage 30, and a coil spring 34 upon said stem and engaging said spider and a collar 35 upon the free end of said stem normally holds the valve 31 in closed position, all valves 31 being closed except during the intake stroke of the corresponding piston.

A compensating, equalizing, or modifying device 36 in a wall of each compartment or chamber 25 includes an inwardly opening check valve 37 adapted to the purpose of allowing entry of air from the atmosphere to each compartment or chamber 25 when it is intended to dilute a too rich explosive mixture from the intake manifold, and each air valve 37 is adjustable independently of all other air valves 37 so that a cylinder can receive an explosive mixture having any desired proportions of gas and air. Each check valve 37 may be constructed in any desired manner, the valve shown being satisfactory. Numeral 38 indicates a tubular member removably threaded as at 39 in the upper wall 40 of each compartment or chamber 25, said member 38 being within the compartment or chamber and having an air inlet passage 41 terminating in a cavity 42 in which the valve 37 is situated. As disclosed, the end of the cavity 42 spaced from the inlet passage 41 threadably receives a suitable nut 43, and a coil spring 44 between the nut 43 and the valve 37 normally holds the valve upon its seat. Preferably, the valve has a stud 45 within the adjacent end of the coil spring. See Fig. 2. It will be evident that the pressure with which the valve 37 rests upon its seat to close the air inlet passage 41 will depend upon the adjustment of the nut 43 in the cavity 42. An opening 46 in the wall of the tubular member and at the inner side of the valve 37 affords communication between the cavity 42 and the compartment or chamber.

It will be obvious that each air valve 37 is adjustable independently of all other air valves, and that each of said air valves can be adjusted to allow the entry of any desired amount of air via the air valve 37 during a suction stroke of a piston to thus dilute a too rich explosive mixture and insure the feeding to each cylinder of an explosive mixture having the desired and proper proportions of gas and air.

It should be remarked that a piston having a tight fit in its cylinder will exert a sucking action which is different from the sucking action of a piston having a loose fit, so that in an ordinary internal combustion engine one cylinder may receive an explosive mixture richer than that received by another cylinder. A separate mixing compartment or chamber 25, with adjustable modifying valve

or device, incorporated for each cylinder makes provision whereby each cylinder can receive explosive mixture having the proportions of gas and air which it is desired to give that cylinder. In other words, the present invention makes provision whereby explosive mixture to be fed to each cylinder can be modified independently of explosive mixture to be fed to all other cylinders, so that the explosive mixture condition in each cylinder is independent of the explosive mixture condition in all other cylinders. 5

10 Numeral 47 denotes a blow out valve, one in a wall 48 of each compartment or chamber 15 25 adapted to care for back firing should this occur in the unifold. As disclosed, each valve 47 has a stem 49 slidably mounted in an overhanging flange 50 of the unifold, and a coil spring 51 upon the stem and between the flange and valve normally holds said valve pressed against an outer seat 52 of an opening 53 in said wall 48. See Fig. 2. Clearly, should an explosion occur in a compartment or mixing chamber 25, the products 20 25 of combustion would escape via the opening 53 against the action of the coil spring 51. 25

The unifold 24 can be made in one piece as disclosed, or there may be separate units constituting each compartment or mixing 30 chamber 25.

Having thus fully described the invention, what I claim as new and desire to secure by Letters Patent is:

1. In an internal combustion engine, a carburetor, a plurality of cylinders, a piston in each cylinder, an intake manifold leading from the carburetor, a plurality of separate mixing chambers all adapted to be communicated with by the intake manifold and each 35 40 45 adapted to communicate with a cylinder, and an adjustable air valve in each mixing chamber adapted to be opened by suction of the piston in the corresponding cylinder to dilute a too rich mixture fed to the mixing chamber via the intake manifold. 100
2. In an internal combustion engine, a carburetor, a plurality of cylinders, a piston in each cylinder, an intake manifold leading from the carburetor, a unifold consisting of 50 55 60 separate mixing chambers one for each cylinder and adapted to be communicated with by said intake manifold, and an inwardly opening adjustable air valve in each mixing chamber adapted to be opened by suction exerted by the piston of the cylinder with which said mixing chamber communicates during the suction stroke of said piston to dilute a too rich mixture in said mixing chamber. 110
3. The combination as specified in claim 1, and a check valve between each mixing chamber and said intake manifold. 115
4. In an internal combustion engine, a cylinder, an explosive mixture intake manifold, a mixing chamber adapted to be communicated with by said intake manifold and 65 70 75 80 85 90 95 105 110 115 120 125 130

adapted to communicate with said cylinder, an inwardly opening adjustable spring pressed valve adapted to allow entry of air to said mixing chamber, and an outwardly opening valve in said mixing chamber constituting a blow out for back firing. 70

5. The combination as specified in claim 1, an outwardly opening valve in each mixing chamber constituting a blow out for back firing, and a check valve between each mixing chamber and said intake manifold. 75

Signed at Bridgeport, in the county of Fairfield, and State of Connecticut, this 24th day of May A. D., 1926.

JOHN V. OSTERHOUT. 80
